UNITED STATES PATENT OFFICE.

OTIS R. ANGELL, OF HAVERHILL, MASSACHUSETTS, ASSIGNOR TO THE HAMEL SHOE MACHINERY COMPANY, A CORPORATION OF MASSACHUSETTS.

HEEL-COVERING MACHINE.

1,281,263.

Specification of Letters Patent. Patented Oct. 15, 1918.

Application filed February 1, 1917, Serial No. 145,947. Renewed December 24, 1917. Serial No. 208,697.

To all whom it may concern:

Be it known that I, OTIS R. ANGELL, a citizen of the United States, residing at Haverhill, in the county of Essex and State 5 of Massachusetts, have invented certain new and useful Improvements in Heel-Covering Machines; and I do declare the following to be a full, clear, and exact description of the invention, such as will enable others skilled 10 in the art to which it appertains to make and use the same.

My invention relates to that class of machines which apply sheet material to the exposed surfaces of the shoe heel for covering 15 the same, the machine herein disclosed being particularly adapted for securing sheet celluloid or like substances to the side and rear surfaces of a wood heel, and the object is to provide a machine of this class which may 20 be simply and inexpensively manufactured and marketed, yet which will be highly efficient and durable.

With the foregoing general object in view, the invention resides in certain novel features of construction and in improved and 25 desirable combinations of parts to be herein-after more fully described and claimed, the descriptive matter being supplemented by the accompanying drawings which consti- 30 tute a part of this application and in which:

Figure 1 is a side elevation of the improved machine;

Fig. 2 is a longitudinal section with parts 35 in elevation;

Figs. 3 and 4 are vertical transverse sections on the lines 3-3 and 4-4 of Fig. 1; and

Fig. 5 is a perspective view of the former which shapes the heel covering to the heel.

In the drawings above briefly described, the numeral 1 has reference to a suitable frame preferably supported by legs 2 from a bench 3, the side bars of said frame constituting a pair of tracks upon which a carriage 4 is slidably supported. As shown in Fig. 4, the side bars of the frame 1 are provided with dovetail grooves 5, one of which is equipped with an inwardly adjustable bar 6, the two grooves 5 receiving a dovetail 8 on the lower side of the carriage 4. Set screws 9 are provided for forcing the bar 6 inwardly to the required extent for taking up wear and preventing side motion of the carriage.

Rising from the carriage 4 is a substan-

tially C-shaped arm 10 which is by preference cast integrally therewith, the upper portion of said arm having a vertical guide 11, while a horizontal guide boss 12 projects from the intermediate portion thereof in a direction parallel with the line of movement of the carriage. A vertical stem 13 is mounted slidably in the guide 11 and a clamping jaw 14 is carried by the lower end of said stem, being preferably swiveled thereto as 65 shown in Figs. 2 and 4. A coiled spring 15 is provided for normally raising the stem 13, a lever 16, however, being employed for forcing said stem downwardly when it is required to engage the jaw 14 with the seat 70 surface of a heel H, the swivel mounting of the jaw 14 permitting the engaging face thereof to adapt itself to the inclination of such heel seat surface. A suitable spring pressed dog 17 is employed for holding the 75 lever 16 in operative position but as soon as this dog is released the spring 15 comes into play to return the parts to their normal 80 positions. Swiveled on the carriage 4 in approximately vertical alinement with the jaw 14 is another jaw 18 for contact with the tread surface of the heel, while a thrust plate 19 is swiveled to a stem 20 projecting into the boss 12 and adjustably secured in place by a set screw 21, said thrust plate being 85 so shaped as to contact throughout its area with the curved breast surface of the heel as shown in Figs. 1 and 2.

The heel clamp just described co-operates with a former 22 whose internal shape corresponds strictly with that of the side and rear surfaces of the heel to be covered, said former being open at its upper and lower ends and at its front side in order that the heel may move into it when the carriage 4 90 is shifted in the proper direction. A cable 23 is connected at one end with the carriage for shifting it into the former 22, while another cable 24 having a weight 25 is provided for returning said carriage, cable 23 100 being connected with a foot pedal or the like not shown. The former 22 consists of a fixed rear section 26 and a pair of wing sections 27 hinged at 28 to the front edges thereof, all of said sections being provided 105 with jackets 29 to successively contain a heating and a cooling medium. The upper and lower ends of the rear section 26 are provided with integral ears 30 secured by screws or the like 31 to the upper and lower 110

ends of a C-shaped arm 32 which rises from the frame 1 at one end of the latter.

A steam or hot water supply pipe 33 and a cold water or air pipe 34 each deliver into 5 a four-way coupling 35 and are respectively provided with cut off valves 36 which are moved to opposite positions by a single movement of the link 37 so that when steam or another heating medium is admitted to 10 the coupling 35 through the pipe 33, the supply of cooling fluid from pipe 34 will be automatically cut off, and vice versa. A pipe 38 leads from the coupling 35 to the upper end of the rear section 26 of the former 15 22 while another pipe 39 leads from said coupling to one of the wings 27, said pipe 39 having a coil 40 to permit it to yield as the aforesaid wing moves outwardly and inwardly. A pipe 39' shown most clearly in 20 Figs. 1 and 2, branches from pipe 39 and leads to the other wing 27, said pipe having a coil 40' acting in the same manner as 40.

An exhaust pipe 41 is provided with two branches 42 and 43 which lead respectively 25 to the fixed section 26 of the former 22 and to one of the wings 27 thereof, the branch 43 being coiled at 44 to permit it to yield as the wing in question moves inwardly or outwardly. A branch 43' having a coil 44' 30 leads from the branch 43 to the other wing 27.

By the arrangement of piping above described, a heating medium may be injected 35 into the jackets 29 by moving the link 27 in one direction, whereas movement of said link in the other direction will cut off the supply of the steam or the like and will inject cold water or air into the jackets to cool them, this being necessary for reasons to be here- 40 inafter fully described.

It is necessary to swing the wings 27 outwardly in order that the heel H may be moved into the former 22, and these wings must be again returned to their normal positions after the heel is properly received in 45 said former. For accomplishing the above results two upright levers 45 are fulcrumed between their ends at 46 to the frame 1, the upper ends of said levers being pivotally and 50 slidably connected with the wings 27 as indicated at 47, while the lower ends of said levers are provided with adjustable shoes 48 shown in Fig. 3, said shoes contacting with a cam 49 rotatable on a shaft 50 and having 55 a crank arm 51 by means of which it may be turned when required to spread the lower ends of the levers 45 for the purpose of bringing the upper ends thereof together to move the wings 27 inwardly. When the cam 60 is shifted in the other direction by the coiled spring 51', a coiled spring 52 which connects the lower ends of the levers 45, and other coiled springs 53 connecting the upper ends 65 of said levers with the wings, coact with said levers to move the wings 27 outwardly.

The entire former is provided with a lining 54 of vulcanized rubber so that regardless of the joint necessary where the hinge connections 28 occur, the interior of the device will be smooth and will not therefore affect 70 the quality of the work. The upper, lower and front edges of the lining 54 are provided with inwardly extending flanges 55 which serve to turn the upper, lower and front edges of the heel covering C over onto 75 the heel H when the latter is forced into the former 22. (See Fig. 2).

In operation, the heel H is positioned in the heel clamp as shown in Fig. 1, the lever 16 is then operated to force the jaw 14 downwardly onto the heel to clamp it against the jaw 18, and the thrust plate 19 is adjusted so that it comes in contact with the front side of the heel. These preliminaries having been carried out, the heel is coated with 80 glue or any other suitable cement which becomes viscous or adhesive when heated, and the sheet of material to be used as the covering is then stood on edge upon the frame 1 so that it rests against the former 22 as 85 shown in dotted lines in Fig. 1. Cable 23 is now operated to shift the carriage 4 so as to move the heel H into contact with the covering C and then into the former 22 in which the covering is shaped to the heel, the upper and lower edges thereof being turned inwardly by the flanges 55 at the upper and lower edges of the lining 54. It is of course understood that during this movement of the heel into the former 22 the wings 27 shall 90 have been swung outwardly but they are now shifted inwardly to their operative positions by operating the lever 51 so as to turn the cam 49 in the required direction. Either before or after moving the heel into 95 the former, the heating medium is allowed to enter the jackets 29 so that the cement or glue with which the heel has been coated is heated and thus the covering is effectively cemented to said heel. This operation having been performed, the steam or the like is cut off and cold water or any other suitable cooling means is admitted into the jackets to cool the glue or cement to cause it to quickly harden and retain the heel covering 100 105 in proper place.

The improved machine will operate to equal advantage for applying any kind of covering to the heel but if celluloid or other comparatively stiff material is to be employed for this purpose, it is well to soften the same by superheated steam or by immersion in ether, or alcohol.

It will also be evident that the former is easily removed from the frame by the removal of a few bolts and pipe connections so that formers of various sizes and shapes as desired may be interchangeably mounted for use with the same clamp.

From the foregoing, taken in connection 130

with the accompanying drawings, it will be seen that although the invention is of comparatively simple and inexpensive nature, it will be highly efficient and durable. For 5 these reasons, the construction shown constitutes the preferred form of the machine, but it is to be understood that within the scope of the invention as claimed, numerous changes may be made without sacrificing the 10 principal advantages. Moreover the machine need not be used identically as described since if required it could be immersed in hot water or the like to heat the cement on the heel instead of employing the 15 jackets 29.

I claim:

1. A heel covering machine comprising a former to receive a heel to be covered, and a clamp for holding said heel, said 20 former and clamp being movable relatively, said clamp comprising relatively fixed and movable jaws for contact with the upper and lower surfaces of the heel, and a thrust device for contact with the front side of said 25 heel.

2. A heel covering machine comprising a former to receive the heel to be covered, a track leading to said former, a carriage 30 slideable along said track and a clamp thereon adapted to hold the heel to be covered and movable into said former, said clamp comprising an arm rising from said carriage, relatively fixed and movable heel-clamping jaws carried by said carriage and 35 arm for contact with the lower and upper surfaces of the heel, and a thrust plate carried by said arm for contact with the front side of said heel.

3. A heel covering machine comprising a 40 former shaped internally to conform to a heel, said former being open at its upper and lower ends and at its front to receive the heel to be covered, and the sides of said former having outwardly swinging wings, 45 said wings and the remainder of the former having a jacket to contain a heating fluid, means for forcing said wings inwardly toward the heel and piping for supplying the jackets with the heating medium, said piping 50 including a pair of pipes extending to the two wings and having coils adapted to yield when said wings are moved inwardly and outwardly.

4. A heel covering machine comprising a 55 base, an arm rising rigidly therefrom, a former shaped to conform to the shape of a heel, upper and lower laterally extending lugs formed integrally with said former and secured to the upper and lower ends of 60 said arm, and means for moving the heel to be covered into said former.

5. A heel covering machine having a former permanently shaped internally to conform to the sides and back of a heel, said former being open at its upper and 65 lower ends and at its front to receive the heel to be covered, and flanges projecting inwardly from the edges of said former to shape the covering around the edges of the heel. 70

6. A heel covering machine having a former shaped internally to conform to the sides and back of a heel, said former being open at its upper and lower ends and at its front to receive the heel to be covered, and 75 having a pair of hingedly mounted side wings attached to swing outwardly and inwardly, a flexible lining in the former extending over the hinge lines of said wings, and inwardly extending flanges on the edges 80 of said lining for turning the edges of the heel covering inwardly around the heel.

7. A heel covering machine comprising, in combination, a mold shaped internally to conform to the sides and rear portion of a 85 heel to be covered, said mold having at least one open side, and a flange-like member constructed and arranged to project inwardly from the edge of said open side for turning in the edge of the covering material. 90

8. In a machine for covering wood heels with celluloid or the like, in combination, a supporting frame, a carriage, a heel clamp mounted thereon, a hollow mold so constructed as to conform to the surface of a heel to be covered, and means for interchangeably mounting said mold upon the frame whereby to permit of the employment of molds of various sizes and shapes. 100

9. In a wood heel covering machine, a frame, a mold mounted thereon and shaped internally to conform to the surface of a heel to be covered and having its forward side portions mounted for relative inward 105 and outward movement, mechanism for moving said portions comprising a pair of oppositely disposed levers fulcrumed upon the frame, means for pivotally connecting one end of each of said levers to the respective movable side portions of the mold, a double cam adapted to move the free ends of the levers in opposite directions, means to return the levers to initial position and means for actuating said cam. 110

In testimony whereof I have hereunto set my hand in the presence of two subscribing witnesses.
